ABSTRACT

A continuous filament for a slide fastener having legs extending from head elements and joined by flattened heels, the legs having notches therein at the junctions with the heels to seat threads for securing the continuous filament to a slide fastener tape and the heels extending substantially transversely from the surfaces of the notches, and a method and apparatus for forming the continuous filament.

CONTINUOUS FILAMENT SLIDE FASTENER

BACKGROUND OF THE INVENTION

1. Field of the Invention

The present invention pertains to slide fasteners and, more particularly, to a continuous filament forming interengaging elements for a slide fastener and a method and apparatus for forming the continuous filament.

2. Description of the Prior Art

Continuous filaments made of a plastic material are conventionally utilized to form interengaging elements for slide fasteners, such continuous filaments being normally of a coil- or ladder-type configuration. In securing ladder-type continuous filaments to fabric slide fastener tapes, the threads extend over and protrude from the legs and heels of the continuous filament; and, thus, slide fasteners utilizing such continuous filaments are subject to wear and abrasion.

While the prior art has contemplated the use of grooves and recesses in filaments to reduce abrasion in slide fasteners, the prior art has not been well accepted due to difficulty in production and further since abrasion and wear have not been reduced to the extent desired. U.S. Pat. No. 3,015,868 is exemplary of specifically configured filaments for slide fasteners and means for securing such filaments to tapes; however, the threads utilized to secure the filaments to the tapes are still exposed to wear and abrasion.

SUMMARY OF THE INVENTION

The present invention is generally characterized in a slide fastener including a tape having an inner edge, a continuous filament forming a plurality of longitudinally spaced head elements, a pair of legs extending from each head element, a plurality of flattened heels joining legs extending from adjacent head elements and a notch formed at a junction between each of the legs and the heels, and thread means for securing the continuous filament to the tape, the thread means being seated in the notches.

Accordingly, it is an object of the present invention to produce a continuous filament for a slide fastener overcoming the disadvantages of the prior art by utilizing notches in the legs of the continuous filament adjacent flattened heels to seat threads for securing the filament to a tape.

Another object of the present invention is to form a continuous filament for a slide fastener with flattened heels extending substantially transversely from the flat surfaces of notches formed in legs of the filament.

A further object of the present invention is to provide a method of forming a continuous filament for a slide fastener wherein an angularly oriented force is utilized to form a notch in the legs of the filament.

The present invention has an additional object in that apparatus for forming a continuous filament includes a forming wheel having cavities for forming notches in the filament in response to an angular force from a sloping side surface of a heeling wheel.

Another object of the present invention is to utilize right-angled corners to form notches and flattened heels in a continuous filament for a slide fastener.

Some of the advantages of the present invention over the prior art are that threads securing the filament to a tape are biased toward the junction of the legs and the heels to stabilize installation, the profile of the tape and filament is reduced, protection is provided against

scuffing by the slider and the threads securing the filament to a tape are contained and protected in notches adjacent heels extending outwardly to leave an unobstructed tape area.

5 Other objects and advantages of the present invention will become apparent from the following description taken in conjunction with the accompanying drawings.

BRIEF DESCRIPTION OF THE DRAWINGS

FIG. 1 is a front elevation of a slide fastener having interengaging elements formed of continuous filaments according to the present invention;

15 FIG. 2 is a section of the slide fastener of FIG. 1 taken along line 2-2;

FIG. 3 is an exploded view of apparatus for forming a continuous filament according to the present invention;

20 FIG. 4 is a front elevation of the apparatus of FIG. 3 during forming of a continuous element according to the present invention.

FIG. 5 is a broken perspective of a continuous filament according to the present invention;

25 FIG. 6 is a top view of a portion of the continuous filament of FIG. 5.

FIG. 7 is a side elevation of a portion of the continuous filament of FIG. 5.

FIG. 8 is an end elevation of the continuous filament of FIG. 5 taken along line 8-8.

DESCRIPTION OF THE PREFERRED EMBODIMENT

A slide fastener 10 having interengaging elements formed of continuous filaments according to the present invention is illustrated in FIG. 1 and includes a pair of fabric tapes 12 and 14 carrying interengaging elements 16 and 18 on the inner edges thereof, respectively. A slider 20 is movable along the elements 16 and 18 to control interengagement thereof and to permit 35 opening and closing of the slide fastener 10. The elements 16 and 18 are each of the "ladder-type" and are each formed of a continuous filament 22 and secured to the fabric tapes 12 and 14 in the same manner. Accordingly, only elements 16 are shown in FIG. 2 to illustrate the manner in which the continuous filaments are secured to the inner edges of the tapes.

As shown in FIGS. 5-8, the continuous filaments 22 forming interengaging elements 16 and 18 are shaped to define head elements 24 adapted to interengage 40 when the slide fastener 10 is closed, a pair of legs 26 and 28 extending from opposite sides of each head element 24 and heels 30 and 32 extending substantially parallel to the inner edges of the tapes on opposite sides thereof, heels 30 joining parallel legs 26 extending from adjacent head elements 24 while heels 32 join parallel legs 28 extending from adjacent head elements 24. Legs 26 and 28 have flat notches 34 and 36 formed on the outer surfaces thereof adjacent heels 30 and 32, respectively, and the heels 30 and 32 are each flattened 45 to have a flat bottom surface and an oblate configuration with a longitudinal axis extending substantially transversely from the notches 34 and 36, respectively, such that the continuous filament 22 is distorted in cross section at the heels 30 and 32 as well as at notches 34 and 36 and head elements 24. As best shown in FIG. 5, a single complete course of the continuous filament 22 between two identical longitudinally

spaced points, such as form A to B, includes a heel 30, a leg 26, a head element 24, a leg 28, a heel 32, a leg 28, a head element 24 and a leg 26 such that each course of the continuous filament 22 includes two head elements 24 and single heels 30 and 32 laterally spaced and longitudinally alternating with each other. Accordingly, the continuous filaments 22 have a plurality of heels 30 longitudinally spaced along the inner surfaces of the tapes 12 and 14 adjacent the inner edges thereof and a plurality of heels 32 longitudinally spaced along the outer surfaces of the tapes 12 and 14 in longitudinally alternating relation with heels 30.

As shown in FIGS. 1 and 2, the continuous filaments 22 are secured to the tapes by thread or yarn 38 which can be either sewn or woven to extend over the legs 26 and 28 and loop around the extending portions to form a "braid" package. The thread 38 is seated in the notches 34 and 36 such that the thread is protected from wear. With the continuous filament 22 secured to the tapes, they are bent about the head elements 24 such that the flat surfaces of notches 34 and 36 slope angularly toward the tapes and the legs 26 and 28 and heels 30 and 32 are positioned against respective opposite sides of the tapes with the flat bottom surfaces of the heels extending substantially perpendicular to the flat surfaces of the notches 34 and 36; and, accordingly, the threads 38 slide toward heels 30 and 32 during installation of the filaments such that the threads are contained at the junctions of the heels and the notches providing the slide fastener with a low profile and positively preventing leg movement. The longitudinal axes of the flattened oblate configuration of the heels 30 and 32 extend at an oblique angle away from the tapes and head elements 24 providing protection from scuffing by movement of the slider 20 and leaving unobstructed areas of the tapes since the flattened cross sections of the heels extend outwardly at an oblique angle away from the tapes and the head elements.

Method and apparatus according to the present invention for forming the continuous filaments 22 will be discussed with reference to FIGS. 3 and 4 wherein a forming wheel 40 has a peripheral surface 41 with an annular channel 42 formed therein, and sets of peripherally spaced guides 44 and 46 are arranged on opposite sides of the channel 42 in transverse alignment, the guides 44 and 46 each having sloping surfaces 48 converging toward the bottom of channel 42. A plurality of lugs 50 are carried on the peripheral surface of the forming wheel 40 on either side of channel 42, each lug 50 being in alignment with one of the guides 44 and 46 such that a front surface of each lug 50 spans the area between forming cavities 54 and 56 defined by the spacing between guides 44 and the spacing between guides 46, respectively. The bottom of channel 42 is defined by a spacer 48, and the channel 42 has radial side walls 60 and 62 extending transversely from the bottom of the channel to define the forming cavities 54 and 56 between the guides 44 and 46, respectively, and to form right-angled corners 63 and 64 with the peripheral surface 41.

A heeling wheel 65 is adapted to be received in channel 42 and includes annular, flat rims 66 and 68 extending from opposite sides thereof and a centrally disposed, annular peripheral rim 70, the radius of central rim 70 being greater than the radius of the side rims 66 and 68 by a distance substantially equal to the length

of the legs 26 and 28 of the continuous filament 22. The heeling wheel 65 has side surfaces 72 and 74 sloping from side rims 66 and 68 toward central rim 70, respectively, the surfaces 72 and 74 having frustoconical configurations with an angular orientation parallel to sloping surfaces 48 on guides 44 and 46.

In order to form a continuous filament 22 according to the present invention, a continuous filament is initially formed in a serpentine configuration, for example by wrapping around the lugs 50, and is then bent into a channel-like configuration with a generally constant filament cross section. The channel-like serpentine filament 76 is positioned in the channel 42 of the forming wheel 40 as shown in FIG. 3 with legs in forming cavities 54 and 56. The heeling wheel 65 is inserted in channel 42, as shown in FIG. 4, such that the filament 76 can be continuously fed to the apparatus while the forming and heeling wheels 40 and 64 are rotated to compress the filament and permit continuous forming of the continuous filaments 22. The heeling wheel 65 is forced into the channel 42 with a force sufficient to deform the filament 76, the side rims 66 and 68 depressing and flattening the heels 30 and 32 against the peripheral surface 41 of the forming wheel and the flat surfaces 52 of the lugs 50. The side surfaces 72 and 74 of the heeling wheel 65 provide an angular force pushing the legs of filament 76 into forming cavities 54 and 56 such that notches 34 and 36 are formed in legs 26 and 28 by side walls 60 and 62, respectively, and corners 63 and 64 provide the generally transverse or substantially perpendicular orientation between the flat bottom surfaces of heels 30 and 32 and the flat inwardly extending surfaces of the notches 34 and 36, respectively. The widened head elements 24 are formed by the spaces between guides 44 and 46 which permit the central rim 70 of the heeling wheel 65 to slightly flatten and bend the transverse legs of the filament 76. The parallel relation of sloping surfaces 48 and side surfaces 72 and 74 permit the forming wheel to accommodate the heeling wheel with precision positioning.

Inasmuch as the present invention is subject to many variations, modifications and changes in detail, it is intended that all matter contained in the foregoing description or shown in the accompanying drawings shall be interpreted as illustrative and not in a limiting sense.

What is claimed is:

1. In a slide fastener the combination comprising a tape having an inner edge and inner portions adjacent the inner edge; a continuous filament having a length and forming a plurality of longitudinally spaced head elements along its length, each head element having opposite sides, first and second legs extending from the opposite sides of each head element and being spaced relative to each other, a first plurality of heels joining said first legs which extend from adjacent head elements, a second plurality of heels joining said second legs which extend from adjacent head elements, the inner edge of said tape being interposed between said first and second legs of the head elements along the length of said filament, a first notch formed at a junction between each first leg and its associated first heel and on the exposed side of each first leg, a second notch formed at a junction between each second leg and its associated second heel and on the exposed side of each second leg;

the first and second notches including opposed sloping surface means on the first and second legs of a head element, the opposed sloping surface means on each first or second leg of a head element being angularly oriented in a direction toward said tape; 5 and

thread means extending between and interconnected to inner portions of said tape and the first and second notches such that said thread means is seated in the first and second notches and said filament is 10 secured to said tape;
said first and second pluralities of heels each having a flattened cross sectional configuration positioned

against respective opposite sides of the tape with the longitudinal axis of the flattened configuration extending at an oblique angle away from the tape and the head elements.

2. A combination as recited in claim 1 wherein the opposed sloping surface means of the first and second notches are sloped in a direction away from the inner edge of said tape, and the first and second heels have flat bottom surfaces extending substantially perpendicularly from the opposed sloping surface means of the respective first and second notches.
